UNITED STATES PATENT OFFICE.

JOHN STASZAK AND FRANK SZTUKOWSKI, OF CUDAHY, WISCONSIN.

BOTTLE-CAP PRINTING AND MAKING MACHINE.

Application filed December 29, 1923. Serial No. 683,425.

To all whom it may concern:

Be it known that we, JOHN STASZAK and FRANK SZTUKOWSKI, citizens of the United States, residing at Cudahy, in the county of Milwaukee and State of Wisconsin, have invented certain new and useful Improvements in Bottle-Cap Printing and Making Machines, of which the following is a specification.

10 The invention relates to a cardboard disk marking and cutting mechanism, and more especially to the class of bottle cap printing and making machines.

The primary object of the invention is 15 the provision of a machine of this character, wherein strip cardboard is fed into position to first be printed to bear the required identification data, and this printing being effected in independent groups of varying 20 colored ink, then these groups of the printed portions of the cardboard being cut into disk form to constitute bottle caps, which are subsequently coated with a waterproofing material to render the same liquid resisting 25 and sanitary, and finally massed or stacked for packaging and the delivery thereof from the machine.

Another object of the invention is the 30 provision of a machine of this character, wherein the printing mechanism is automatically inked and the electrotype printing plates interchangeably and removably mounted in said mechanism, while the waterproof coating mechanism is of novel form, 35 and the massing or stacking mechanism of unique construction.

A further object of the invention is the 40 provision of a machine of this character, wherein the mechanisms for effecting the various steps of the printing and cutting of the bottle caps, and also the massing and stacking thereof, are actuated and timed for successive operation to assure the automatic continuous working of the machine as 45 a unit.

A still further object of the invention is the provision of a machine of this character, 50 wherein the same in its entirety is of novel construction, thoroughly reliable and efficient in operation, strong, durable and comparatively inexpensive to manufacture and install.

Other objects will be in part obvious and in part hereinafter pointed out.

The improvements in details and arrangement of parts will be apparent from an inspection of the accompanying drawings, in connection with the specific description hereinafter contained, and wherein the preferred embodiment of the invention is disclosed for the purpose of imparting a full understanding of the same. 55

In the accompanying drawings:

Figure 1, is a transversely broken side elevation of the machine constructed in accordance with the invention. 65

Figure 2, is a vertical longitudinal sectional elevation of the same.

Figure 3, is a vertical transverse sectional elevation taken on the line 3—3 of Figure 1. 70

Figure 4, is an end elevation.

Figure 5, is a top plan view of the machine.

Figure 6, is a fragmentary enlarged vertical sectional view showing in detail the 75 waterproof coating and massing and stacking mechanisms of the machine.

Figure 7, is a detail sectional view on the line 7—7 of Figure 2.

Figure 8, is a fragmentary detail sectional 80 view through the rack bar, showing the rack pinion in mesh engagement therewith.

Similar reference characters indicate corresponding parts throughout the several views in the drawings. 85

Referring to the drawings in detail, A, designates generally the table or stand of the machine, and includes spaced vertical legs 10, and horizontally disposed spaced longitudinal side sills 11, supported by the latter, said sills being preferably of I-beam shape in cross-section and are bolted or otherwise secured to the legs to form a unitary structure. 90

Above the table or stand A, at one end thereof and extending for a distance over the same is a superposed deck 12, constituting a printing and cutting bed 13, the same being supported by uprights or columns 14 and 15, respectively, rising from opposite sides of the table or stand. At the feed end of the table or stand A, and suitably journaled between the sills 11, thereof is a guide roll 16, over which is adapted to be trained the strip of cardboard 17, which is also passed over an upper guide roller 18, journaled between the columns 14, at the feed end of the deck 12, and this cardboard is 100 105

fed onto the bed 13, by means of the feed roll 19 and tension or presser roll 20, respectively, the latter being journaled in bearings 21, while the shaft 22, of the feed roll 19, 5 is journaled in the side bars 23, of the deck 12.

Suitably secured to and rising from the deck 12, are pairs of spaced cross-head guides 24, for a vertically movable cross-head 25, which is fitted with upper and lower rollers 26, 27, working directly against actuating cams 28 and 29, respectively, which are fast upon a driven shaft 30, journaled at 31, in bearing caps 32, mounted 10 on the guides 24, the shaft 30 being fitted at one end with a beveled pinion 33, meshing with a companion gear 34, on the main shaft 35, disposed transversely of the deck 12, and journaled in the columns 15, the 15 said shaft 35, being fitted with the usual fly wheel and belt pulley 36, over which latter is adapted to be trained a belt (not shown) 20 operated from any suitable source of power for actuating the machine.

25 The cross head 25, carries a series of electrotype holders 38, on each of which is removably fitted an electrotype 39, for the printing of the cardboard 17, in a manner presently described. Mounted on the 30 cross head 25, inwardly of the series of holders 38, is a series of disc punches or cutters 40, and a shearing blade 41, the latter being designed to shear the scrap from the cardboard strip 17, while the punches 35 or cutters are adapted to cut the disk bottle caps 42, from the cardboard strip in the operation of the machine.

Upon the bed 13, of the deck 12, is a 40 printing platen 43, for the cardboard strip 17, while transversely of said platen on opposite sides of the printing area thereof are guide tracks 44, for an inking device, including spaced inking rollers 45, and an intermediate distributing roller 46, these rollers being mounted in a carriage 47, which is adapted to travel tracks 44, when shifted transversely of the platen to play against an ink spreading plate 48, removably supported in the cross head guides 24, above the 45 tracks 44, the plate being formed with suitable openings for the electrotype holders 38, to permit the electrotypes 39, to print the cardboard 17, when the cross-head 25, is lowered for this purpose.

55 At one side edge of the spreading plate 48, is an ink font 49, having therein an ink supply roll 50, to furnish ink to the inking rolls 45, the carriage 47, being connected with sprocket chains 51, engaged over sprocket wheels 52, journaled in supports 53, projecting laterally from opposite sides of the deck 12, and on one of the journals of a pair of the sprocket wheels 52, is a rack pinion 54, with which meshes a rack bar 55, eccentrically connected through the medium

of a wrist-pin 56, with a gear wheel 57, mounted on one end of a counter shaft 58, journaled in the caps 32, and this gear 57, meshes with a pinion 59, carried on the shaft 30, so that motion from the latter is 70 imparted to the rack bar 55, which in its reciprocating movement effects the back and forth movement of the inking device, as will be apparent.

On the main shaft 35 is an eccentric 60, 75 embraced by an eccentric strap 61, carried at one end of a shift rod 62, the same being connected at its other end with one arm of a bell-crank lever 63, mounted on a stud 64, at one side of the deck 12, for rocking movement, the other arm of this crank lever 63, being connected with a slide rod 65, carrying a resilient hook like dog 66, which is adapted to co-act with a ratchet wheel 67, 80 fixed to the journal or shaft 22 of the feed roll 19, so that the latter is intermittently moved to feed the cardboard in a step by 85 step manner on the platen 43, as will be obvious.

Arranged between the sills 11, of the table or stand A, at the delivery end portion thereof is a conveyor, including a pair of spaced endless sprocket chains 68, which are trained over sprocket wheels 69, the journals 70, of which have their bearing in 90 the sills 11, and one of these journals 70, exteriorly of the table or stand carries a ratchet wheel 71, with which engages a resilient hook like dog 72, mounted on the end of a shiftable rod 73, which has its other end pivoted to an intermediate arm 74, of the bell-crank lever 63, and in this manner a 95 step by step movement is imparted to the conveyor, the dog 72, being held in positive engagement with the ratchet wheel 71, 100 through the medium of the retaining spring 75, as is shown in Figure 1, of the drawings.

The opposed links of the chains 68, have 105 connected therewith transversely disposed flights 76, so that said pair of chains are connected together, while carried on each flight 76, is a series of disk receivers 77, for retaining disks deposited therein in a manner presently described.

110 Supported by cross pieces 78, suitably mounted in the table or stand A, are separator strips 79, which serve to maintain the disks in rows when being moved by the conveyor, these strips 79, being spaced from each other and disposed longitudinally of 115 the table or stand, as shown in Figure 5, of the drawings.

Above the inner end of the conveyor and supported upon the top edges of the sills 11, 120 of the table or stand A, is a tray 80, in the bottom portion of which is arranged suitable heating units 81, while within this tray 125 is held a tank 82, containing a waterproofing liquid, for example paraffine, the units 81, being designed to maintain the con- 130

tents of the tank 82, liquid, and working within said tank are coating rolls 83, between which pass the disks 42, so that the same will be coated with the liquid for rendering the same waterproof and sanitary.

Located between the lower halves of the rolls 83, is a dispensing chute 84, which receives the disks when passing from between the rolls 83, and delivering them into the receivers 77, the lower portion of the said chute being so constructed and formed to properly deliver the disks, as is clearly shown in Figure 6, of the drawings.

The supply roll 50, within the ink font 49, on its journal exteriorly of the latter, has mounted thereon a ratchet wheel 85, with which engages a ratchet pawl 86, carried upon a ratchet lever 87, the same being swingingly supported on the journal of said roll 50, and this lever is also connected through the medium of a link 88, with the cross head 25, so that when the latter is moved the ink supply roll 50 will be actuated for the delivery of ink from the font onto the inking roller 45.

Depending from the bed 13 of the deck 12, is a delivering spout 89, while the tank 82, beneath the latter has a tip 90, which is disposed directly between the coating rolls 83, and is in register with the said spout 89, to deliver disks between said rolls 83, for the coating thereof with waterproofing material in the form of liquid. The spout 89, has formed therein staggered reversely inclined chutes 91 and 92, respectively, which communicate with the circular openings 93, for the punches or cutters 40, and these chutes present rocker ledges 94, therein to tilt the disks 42, falling therein from the openings 93, so that the printed sides of said disks will face toward the left-hand roll 83, and as the disks pass between both rolls 83, they will be directed tangentially into the lower chute 84, whence the said disks will be discharged onto the conveyor.

Carried by the main shaft 35 is a sprocket wheel 95, over which is trained a sprocket chain 96, the same being also trained over a sprocket wheel 97, carried by the journal 98, of one of the coating rolls 83, so that the same will be positively driven from the main shaft.

Connected with the delivery end of the table or stand A, is a massing or grouping platform 99, having runways 100. Formed thereon, are packaging mouth tubes 101, over each of which is adapted to be slipped a carton 102, whereby the massed disks can be introduced therein expeditiously by an attendant, the massed disks 42, being grouped in preferably five hundred lots, and separated by removable blocks 103, as is in Figure 6, of the drawings.

The journals of the coating rolls 83, exteriorly of the tank 82, at its side opposite

the location of the sprocket wheel 97, carry meshing gears 104, so that the rolls 83, rotate in unison in reverse directions to each other, for the feeding of the disks 42 therebetween, as will be apparent.

At the delivery end of the table or stand A, is mounted a fingered pick up plate 105, which is designed to straighten and pick up the disks from the receivers 77, as the conveyor travels, to bring said disks onto the platform 99, for the automatic stacking and massing thereof, as is shown in Figure 6, of the drawings.

Beneath the shearing blade 41, and formed on the deck 12, is a scrap discharging incline 106, for the waste material cut from the cardboard strip after the disks have been cut therefrom.

The platform 100, is supported by a prop or leg 107, which is fastened at 108, to a depending bracket 109, on the underside of the platform.

The tank 82, for the waterproof liquid 110, is preferably covered with asbestos or other insulating material 111, to enable the heat to be retained within the tank and thereby maintain the liquid at the proper fluidity, while the tray 80, carries a suitable thermometer 112, to determine the degree of heat within the tank, the heating units 81, being controlled in any suitable manner to regulate the heat. The coating rolls 83, are of hollow formation and likewise their journals 98, to permit the introduction of suitable heating elements therein should the occasion require.

The machine is equipped with a suitable commercial counter 123, having an audible signal such as a bell 114, the counter being constructed and arranged to sound its signal when five hundred disks 42, have been massed or grouped, and the conveyor has exactly one hundred flights 76, in its entire length, while one of these flights is suitably marked in a conspicuous manner and the signal is so timed to sound when the marked flight is in view. The attendant or operator of the machine can then place a tag of suitable character under the disk 42 in the receiver 77, containing the same on the marked flight. When the tag is in an upright position in the guide way 100, on the platform 99, the disks 42, are separated at the location of the tag and the block 103, inserted between the groups of disks, and the tag being then removed. In this manner the disks 42, are grouped into masses of five hundred each, for the subsequently packaging of such groups by another machine.

The ink font is formed with a partition 115, so as to divide the same into independent compartments for holding two colors of ink, the electrotype holder 38, and punches 40, being arranged in rows of four in number transversely of the machine. The first two

rows of four electrotypes 39, transversely of the printing bed 13, have one color of ink applied thereto, while the remaining group or series of electrotypes have another color of ink applied thereto, so that the cardboard 17, will be printed in two colors, yet this may be changed at the option of the user of the machine.

In the operation of the machine the same takes the cardboard strip 17, which is trained over the rollers 16 and 18, respectively, and delivered to the bed 13, by the feed roll 19, and tension or presser roll 20, whereupon it is printed by the electrotypes 39, and subsequently cut into disks 42, by the punches 40, the disks being discharged into the chutes 91 and 92, respectively, and thence between the rolls 83, where the same are covered with a waterproof substance, and thereafter are discharged into the receivers 77, on the conveyor, which latter carries the disks 42, to the pick up plate 105, and these disks are finally massed and separated by the blocks 103, into groups of five hundred each, for delivery through the tubes 101, into cartons 102, for the packaging thereof by another machine.

It is of course understood that the various operating parts of the machine are properly timed to assure the successful working of the same, and a continuity of operation.

What is claimed is:

1. A machine of the character described, comprising a stand, a deck supported above the stand at one end thereof and having a printing bed, guides rising from the deck, a cross-head movably mounted between the guides, electrotype holders on the cross-head, detachable electrotypes on the holders, an ink spreading plate above the bed and through which move the electrotypes, inking mechanism movable over the plate, means for feeding a cardboard strip over the bed, guides on the stand and deck for the cardboard, means for cutting the cardboard into disk forms at the printed areas thereof, means for actuating the cross-head, and mechanism for coating the disks with a waterproofing substance.

2. A machine of the character described, comprising a stand, a deck supported above the stand at one end thereof and having a printing bed, guides rising from the deck, a cross-head movably mounted between the guides, electrotype holders on the cross-head, detachable electrotypes on the holders, an ink spreading plate above the bed and through which the electrotypes move, inking mechanism movable over the plate, means for feeding a cardboard strip over the bed, guides on the stand and deck for the cardboard strip, means for cutting the cardboard strip into disk forms at the printed areas thereof, means for actuating the cross-head, mechanism for coating the

disks with a waterproofing substance, and mechanism for conveying the disks successively and massing the same.

3. A machine of the character described, comprising a stand, a deck supported above the stand at one end thereof and having a printing bed, guides rising from the deck, a cross-head movably mounted between the guides, electrotype holders on the cross-head, detachable electrotypes on the holders, an ink spreading plate above the bed and through which move the electrotypes, inking mechanism movable over the plate, means for feeding a cardboard strip over the bed, guides on the stand and deck for the cardboard strip, means for cutting the cardboard strip into disk forms at the printed areas thereof, means for actuating the cross-head, mechanism for coating the disks with a waterproofing substance, mechanism for conveying the disks successively and massing the same, and means for separating the massed disks into groups of predetermined numbers.

4. A machine of the character described, comprising a stand, a deck supported above the stand at one end thereof, and having a printing bed, guides rising from the deck, a cross-head movably mounted between the guides, electrotype holders on the cross-head, detachable electrotypes on the holders, an ink spreading plate above the bed and through which move the electrotypes, inking mechanism movable over the plate, means for feeding a cardboard strip over the bed, guides on the stand and deck for the cardboard strip, means for cutting the cardboard strip into disk forms at the printed areas thereof, means for actuating the cross-head, mechanism for coating the disks with a waterproofing substance, mechanism for conveying the disks successively and massing the same, means for separating the massed disks into groups of predetermined numbers, and means for actuating the inking mechanism.

5. A machine of the character described, comprising a stand, a deck above the stand at one end thereof, and having a printing bed, guides rising from the deck, a cross-head movably mounted between the guides, electrotype holders on the cross-head, detachable electrotypes on the holders, an ink spreading plate above the bed and through which move the electrotypes, inking mechanism movable over the plate, means for feeding a cardboard strip over the bed, guides on the stand and deck for the cardboard strip, means for cutting the cardboard strip into disk forms at the printed areas thereof, means for actuating the cross-head, mechanism for coating the disks with a waterproofing substance, mechanism for conveying the disks successively and massing the same, means for separating the

massed disks into groups of predetermined numbers, means for actuating the inking mechanism, and means operated by the cross head for supplying ink to the inking mechanism.

6. A machine of the character described, comprising a stand, a deck above the stand at one end thereof, and having a printing bed, guides rising from the deck, a cross head movably mounted between the guides, electrotype holders on the cross-head, detachable electrotypes on the holders, an ink spreading plate above the bed and through which move the electrotypes, inking mechanism movable over the plate, means for feeding a cardboard strip over the bed, guides on the stand and deck for the cardboard strip, means for cutting the cardboard strip into disk forms at the printed areas thereof, means for actuating the cross head, mechanism for conveying the disks successively and massing the same, means for separating the massed disks into groups of predetermined numbers, means for actuating the inking mechanism, means operated by the cross head for supplying ink to the inking mechanism, and for shearing the scrap from the cardboard strip.

7. A machine of the character described, comprising a stand, a deck above the stand at one end thereof, and having a printing bed, guides rising from the deck, a cross head movably mounted between the guides, electrotype holders on the cross head, detachable electrotypes on the holders, an ink spreading plate above the bed and through which move the electrotypes, inking mechanism movable over the plate, means for feeding a cardboard strip over the bed, guides on the stand and deck for the cardboard strip, means for cutting the cardboard strip into disk forms at the printed areas thereof, means for actuating the cross head, mechanism for conveying the disks successively and massing the same, means for separating the massed disks into groups of predetermined numbers, means for actuating the inking mechanism, means operated by the cross head for supplying ink to the inking mechanism, means for shearing the scrap from the cardboard strip, and means for injecting the grouped disks into cartons for packaging thereof.

8. A machine of the character described, comprising a stand, a deck above the stand at one end thereof, and having a printing bed, guides rising from the deck, a cross head movably mounted between the guides, electrotype holders on the cross head, detachable electrotypes on the holders, an ink spreading plate above the bed and through which move the electrotypes, inking mechanism movable over the plate, means for feeding a cardboard strip over the bed, guides on the stand and deck for the card-

board strip, means for cutting the cardboard strip into disk forms at the printing areas thereof, means for actuating the cross head, mechanism for conveying the disks successively and massing the same, means for separating the massed disks into groups of predetermined numbers, means for actuating the inking mechanism, means operated by the cross head for supplying ink to the inking mechanism, means for shearing the scrap from the cardboard strip, means for injecting the grouped disks into cartons for packaging thereof, mechanism for coating the disks with a waterproofing substance and heating means for the coating mechanism.

9. A machine of the character described, comprising a stand, a deck above the same, and having a printing bed, guides rising from the deck, a cross head movably mounted between the guides, electrotype holders on the cross head, detachable electrotypes on the holders, an ink spreading plate above the bed, and through which move the electrotypes, inking mechanism movable over the plate, means for feeding a cardboard strip over the bed, guides on the stand and deck for the cardboard strip, means for cutting the strip into disk forms at the printed areas thereof, means for actuating the cross head, mechanism for conveying the disks successively and massing the same, means for separating the massed disks into groups of predetermined numbers, means for actuating the inking mechanism, means operated by the cross head for supplying ink to the inking mechanism, means for shearing the scrap from the cardboard strip, means for injecting the grouped disks into cartons for packaging thereof, mechanism for coating the disks with a waterproofing substance, heating means for the coating mechanism, and mechanism for actuating the feeding means, coating mechanism and conveyor mechanism.

10. A machine of the character described, comprising a stand, a deck above the stand, and having a printing bed, guides rising from the deck, a cross head movably mounted between the guides, electrotype holders on the cross head, detachable electrotypes on the holders, an ink spreading plate above the bed and through which move the electrotypes, inking mechanism movable over the plate, means for feeding a cardboard strip over the bed, guides on the stand and deck for the cardboard strip, means for cutting the strip into disk forms at the printed areas thereof, means for actuating the cross head, mechanism for conveying the disks successively and massing the same, means for separating the massed disks into groups of predetermined numbers, means for actuating the inking mechanism, means operated by the cross head for

supplying ink to the inking mechanism, means for shearing the scrap from the cardboard strip, means for injecting the grouped disks into cartons for packaging thereof, mechanism for coating the disks with a waterproofing substance, heating means for the coating mechanism, mechanism for actuating the feeding means, coating mecha-

nism and conveyor mechanism, and disk retaining means for the conveyor mechanism.

In testimony whereof we affix our signatures.

JOHN STASZAK.
FRANK SZTUKOWSKI
